UNITED STATES PATENT OFFICE.

ANDREW MRAULA, OF EUREKA, CALIFORNIA.

MASSAGING MACHINE.

Application filed August 14, 1924. Serial No. 782,037.

My invention relates to a massaging machine for treating nervous diseases and similar ailments.

An object of the invention is to provide a machine having an electrically heated massaging element, mechanically operated to facilitate the rubbing of various parts of the body, whereby the nervous system can be treated.

10 A further object of the invention is to provide a device of this character which is simple and durable in construction, reliable and efficient in use, and inexpensive to manufacture.

15 Other objects and advantages of the invention will be apparent during the course of the following description.

In the accompanying drawings, forming a part of this specification and in which like numerals are employed to designate like parts throughout the same,

Fig. 1, is a top plan view of the machine,

Fig. 2 is a side elevation of the same,

Fig. 3, is a bottom plan view with the base 25 removed,

Fig. 4, is a front end view of the same,

Fig. 5, is a rear end view of the same,

Fig. 6, is a fragmentary cross sectional view showing the electrical connections,

30 Fig. 7, is a horizontal cross section of the massaging element, and,

Fig. 8, is a fragmentary side elevation of the electrical connections.

In the drawings, wherein for the purpose 35 of illustration I have shown a preferred embodiment of my invention, the numeral 5 denotes the main frame composed of complementary upper and lower sections 6 and 7 clamped together by bolts 8, the lower sec-

40 tion 7 being mounted on the base board 9 and secured thereto, at its sides and ends, by bolts 10. The frame is relatively narrow and each section has a semi-circular recess on one end, providing a seat for the electric motor 11 which is clamped between the sections extending beyond the sides thereof. At the opposite end of the frame are a pair of longitudinally extending arms 12 disposed in spaced superimposed relation.

45 The arms have concaved grooves 13 on their inner sides in which the U-shaped frame 14 is slidably mounted. The frame 14 is formed from a pair of L-shaped members 15 and 16 joined together by lugs and bolts 17. To impart a reciprocating motion to the

end are connected to the center of the frame on opposite sides thereof, as at 18', the cranks being bowed outwardly and eccentrically connected at their opposite ends to the disks 19, as at 19', mounted on the ends of the shaft 20 of the motor 11.

A flat massaging element 21 is clamped at its center along its longitudinal edges between the flanges 22 formed integral with the sides of the U-shaped frame 14, by bolts 23. The massaging element extends beyond the end of the frame and consists of a core 24 having a coil of wire 24' at each end, the whole being completely enclosed by the casting 25. The wires connecting the coils and leading to and from the massaging element pass along the central longitudinal grooves 26 extending the length of the sides of the U-shaped frame. The wires from the massaging element are respectively connected with the terminals 27 mounted on opposite sides of the frame at its lower rear corner. Each terminal carries a brush 28 having sliding contact with the contact strips 29 mounted on the insulating blocks 30 seated in the arm 12 of the lower section 7 of the frame near the motor. One of the contact strips is connected with the terminal 31 and the other with the terminal 32 mounted in a recess 32' in the lower section 7. A terminal 33 is mounted adjacent the terminal 32 and wires 34 and 34' lead from each of the terminals 31 and 32 to the motor. A cable 35 has connection with the terminals 32 and 33 and passes through an opening 35' in the section 7 having its free end equipped with a plug 36 adapted to be connected with a source of current to run the motor and heat the wire coils of the massaging element.

In use, the fingers of the hand are folded against the palm as illustrated in Fig. 3, and the nails of the fingers placed against the sides of the massaging element. The motor is then started causing the massaging element to reciprocate, rubbing the nails vigorously and at the same time permitting the heat waves from the massaging element to pass through the nervous system of the body. This treatment will stimulate the nerves and will produce effective results in the treatment of nervous diseases.

It is to be understood that the form of my invention herewith shown and described is to be taken as a preferred example of the same and that certain changes in the shape, size and arrangement of the parts may

be made without departing from the spirit of the invention or the scope of the subjoined claims.

Having thus described my invention, I claim:

1. A machine of the character described comprising a frame composed of separable sections having longitudinally extending arms disposed in spaced superimposed relation, a U-shaped frame slidably mounted between said arms, a massaging element clamped within said U-shaped frame, heating coils carried by said massaging element, a motor mounted within said first mentioned frame, cranks connecting the motor with said U-shaped frame and a source of energy connected with said motor and heating coils.

2. A machine of the character described comprising a frame composed of upper and lower sections, a motor clamped between said sections, a U-shaped frame slidably mounted between said sections, a massaging element mounted within said U-shaped frame, heating coils carried by said massaging element, means connecting said motor with said massaging element adapted to reciprocate the latter and a source of energy connected with said motor and heating coils.

3. A machine of the character described comprising a frame having longitudinally extending spaced arms, a U-shaped frame slidably mounted between said arms, a massaging element clamped within said U-shaped frame, heating coils carried by said massaging element, stationary contacts mounted on said lower arm, a source of energy connected with said stationary contacts, contacts attached to said U-shaped frame

having connection with said heating coils, adapted to slidably engage said stationary contacts and means for reciprocating said U-shaped frame.

4. A machine of the character described comprising a main frame, a U-shaped frame slidably mounted in said main frame, a massaging element clamped within said U-shaped frame, heating coils carried by said massaging element, a motor mounted in said main frame adapted to reciprocate said U-shaped frame, stationary contacts carried by said main frame, a source of energy connected with said motor and stationary contacts, and movable contacts carried by said U-shaped frame having connection with said heating coils, adapted to engage said stationary contacts.

5. A machine of the character described comprising a main frame, a U-shaped frame slidably mounted in said main frame, a massaging element clamped within said U-shaped frame, a motor mounted in said main frame, cranks connecting said motor with said U-shaped frame, and a source of energy connected with said motor.

6. A machine of the character described comprising a main frame composed of upper and lower sections, a motor clamped between said sections, a U-shaped frame slidably mounted between said sections, a massaging element clamped within said U-shaped frame, cranks connecting said motor with said U-shaped frame adapted to reciprocate the latter, and a source of energy connected with said motor.

In testimony whereof I affix my signature.
ANDREW MRAULA.
